CENTRIFUGAL SWITCHING DEVICE.

1,150,010.

Specification of Letters Patent.

Patented Aug. 17, 1915.

Application filed June 14, 1912. Serial No. 703,677.

To all whom it may concern:

Be it known that I, STANLEY L. ARMSTRONG, a citizen of the United States, and a resident of Pittsburgh, in the county of 5 Allegheny and State of Pennsylvania, have invented a new and useful Improvement in Centrifugal Switching Devices, of which the following is a specification.

My invention relates to centrifugal 10 switching devices and it has special reference to speed-limit devices such as are employed in connection with rotary converters and other dynamo-electric machines for the purpose of preventing excessive speeds.

One of the objects of my invention is to 15 provide a device of the above-indicated character that shall be simple and durable in construction, effective and reliable in operation, and be so constructed as to operate 20 with uniformity and positiveness.

In the prior art, it has been customary to employ devices of this general character for similar purposes, but such devices have usually been constructed and operated in substantially the manner of engine shaft governors which are particularly adapted for speed regulation and in which the centrifugally actuated weighted member is moved slowly to its outward position, in accordance 25

30 with the increase of speed. Hence, the switching devices which are adapted to be actuated by the weighted members, have been subjected to a series of light blows prior to the time when the weighted tripping member reaches its full outer position, and the operation thereof has therefore been unreliable and unsatisfactory. Furthermore, the spring which is usually employed 35

40 for restraining the centrifugally actuated member in its inner position has been so disposed that it has been subjected to excessive distortions during the operation of the device, whereby a certain amount of "set" has been produced therein which has resulted in 45 non-uniformity of operation.

According to my present invention, I provide 50 a speed limit device embodying a weighted pivotally mounted member which is adapted to be moved outwardly by centrifugal force and with which is associated a plurality of links forming a toggle, and a tension spring that is attached substantially at the middle of the central member of the mechanism and is disposed substantially 55 parallel to the outer link member. Thus,

the spring acts upon the linkage in a direction substantially at right angles to the direction of movement of that portion of the linkage to which it is attached and, by reason of this peculiar construction and arrangement of parts, the elongation of the spring is reduced to a minimum. Furthermore, the construction of the device is such that, when a predetermined speed is attained, the torque on the weighted member 60 produced by centrifugal force predominates over that effected by the spring and, consequently, said member is moved outwardly into its outer position. The arrangement of parts and proportions thereof are so chosen 65 that, after the weighted member starts to move outwardly, it is caused to move the entire distance quickly, and no intermediate positions can be maintained. Thus, a positive action of the tripping device is secured 70 and a single effective blow is delivered to the switching device, whereby its operation is rendered definite and reliable.

My invention may best be understood by 75 reference to the single figure of the accompanying drawing, which is a view, partially in end elevation and partially in section, of a device constructed in accordance with my invention.

Referring to the drawing, the device here 80 shown comprises a tripping device 1 and a switching device 2, said tripping device 1 comprising essentially a rotatable shaft 3, a pivotally mounted weighted arm 4, a second pivotally mounted arm 5, a connecting link 90 6, a spring 7 and a main body or supporting member 8 with which said parts are associated.

The switching device 2 is conveniently 95 secured to a lug 9 which forms an integral 100 part of a supporting bearing or pedestal 10 for the shaft 3, and said switching device comprises a casing or box 11, a plurality of stationary contact terminals 12, a cooperating movable contact member 13, an actuating spring 14, a latch 15 and a pawl or dog 16 which is adapted to be engaged and actuated by the weighted member 4 when it occupies its outer position.

The main body member 8 is substantially 105 cylindrical in form, having an outwardly projecting peripheral flange 18 that is provided with an opening 19 for the purpose of permitting unrestricted operation of the weighted arm 4, and said member 8 is suit- 110

ably secured to the shaft 3. The arm 4 is pivotally connected to the supporting member 8 by a stud 20 and its outer end is provided with a weighted portion 21. One end of the arm 5 is pivotally connected to the body member 8 by a stud 22 and the link is interposed between its free end and the weighted end of the arm 4. The link 6 is disposed substantially at right angles to the arm 5, and the spring 7 is attached thereto at approximately its middle point, said spring 7 being disposed substantially parallel to the arm 5. The other end of the spring 7 is suitably secured to a lug 23 on the body member 8, and said spring is normally maintained in tension, tending to restrain the weighted member 4 in its inner initial position. The tension of the spring 7 may be varied, as desired, by means of a suitable 10 adjustable connecting device 24 that is employed between the spring and the link 6.

When the shaft 3 is at rest or is rotated at less than the speed for which the tripping device 1 is adjusted to operate, the weighted 15 arm 4 is maintained in its inner position by the spring 7 against a suitable stop 26. Inasmuch as the spring 7 is disposed substantially parallel to the arm 5, there is no component force tending to rotate said arm about its pivotal support 22. However, by reason of the relationship of the weighted arm 4, with respect to the link 6 and the spring 7, said arm is acted upon by a force 20 tending to rotate it in a counter-clockwise direction, whereby the linkage is maintained in its inner position against the stop 26.

The stationary contact terminals 12 are suitably mounted upon an insulating block 27 that is secured to the bottom of the casing 25 or box 11 and, connected to said terminals, are conductors 28 which project through insulating bushings 29 that are provided in the back wall of the casing 11.

The movable contact member 13 is adapted 40 to coöperate with and bridge across the stationary contact terminals 12 and is suitably mounted upon a supporting rod 30 and insulated therefrom. The rod 30 is vertically movable in a bearing or bracket member 31 and is provided with a downwardly 45 projecting extension 32 which projects through the bottom wall of the casing 11 and the end of which is provided with a button 33. The spring 14 surrounds the rod 30 and is disposed between the bearing bracket 50 31 and the insulated movable contact member 13 and tends to actuate the rod 30 and its associated movable contact member 13 in a downward direction whereby said contact 55 member is maintained in coöperative engagement with the contact terminals 12 when the switch is closed. The upper end 60 of the rod 30 is provided with a pin 35 which is normally adapted to rest upon the 65 upper edge 36 of the movable latch 15. The

upper edge of the latch 15 is provided with a recess or depression 37 which is located immediately adjacent to that portion of the latch on which the pin 35 normally rests. A spring 38 is interposed between the latch 15 and the casing 11 and tends to maintain the latch in its extreme right-hand position. One end of the latch 15 is supported upon a stud 39 and is provided with a downwardly 70 projecting portion 40 which serves as a stop and restricts the movement of the latch in a longitudinal direction to the right. The other end of the latch 15 is pivotally connected to an arm 41 which constitutes a part of the pawl or dog 16, said member being 75 pivotally mounted upon a projecting bracket 42 which forms a part of the casing 11.

Assuming the various parts to occupy the 80 positions shown, the operation of the device is as follows: Below the critical speed for which the device is adjusted to operate, the weighted member 4 and the members 5 and 6, which constitute a toggle between the member 4 and the body member 8, are maintained in their initial inner position, as hereinbefore set forth. If the speed of the shaft 3 increases to that for which the device is adjusted, the torque produced by the centrifugal force acting upon the weighted portion 21 and tending to rotate the arm 4 in a clockwise direction, predominates over the torque which is effected through the agency of the spring 7 and tends to hold the arm 4 in its normal position. Hence, the resultant 85 force on the weighted arm 4 causes said arm to be moved outwardly and, by reason of the peculiar arrangement of parts, the arm is thrown suddenly to its outer position after once being moved from its normal position. The reason for this positive action resides in the fact that the elongation of the spring 7 is relatively slight and, hence, when the weighted arm 4 once starts to move outwardly, the centrifugal force acting thereon 90 increases more rapidly than the tension of the spring 7. Furthermore, as the arm 4 is moved outwardly, the lever arm through which the centrifugal force acts in producing a torque about the pivotal support 20 is 95 decreased at a slower rate than the arm through which the spring 7 acts in opposition thereto. Furthermore, although there is no component force tending to rotate the arm 5 when the speed is normal, as soon as 100 any movement of the linkage mechanism is effected, the spring 7 is slightly displaced in position toward the right, thus causing a slight force tending to effect a clockwise rotation of the arm 5. This force tends to assist the centrifugal force acting on the weighted portion 21 in throwing the weighted member 4 to its outer position. It is, therefore, evident that no intermediate positions of the weighted member 4 can be main- 105 110 115 120 125 130

tained and that the member is thrown to its full outer position with a quick movement when the speed exceeds a predetermined value. Manifestly, when the weighted portion 5 21 occupies its full outer position, it delivers a positive blow to the pawl 16, thereby forcing the latch 15 to the left against the action of the spring 38. In so doing, the pin 35 is allowed to drop into the recess 37 10 and the movable contact member 13 is forced downwardly into coöperative engagement with the stationary contact terminals 12 by means of the spring 14. In order to reset the switching device 2, it is only necessary 15 to push the rod 30 upwardly by means of the button 33, thereby raising the pin 35 out of engagement with the sides of the recess 37, after which the latch 15 is drawn to its extreme right position through the agency 20 of the spring 38, in which position the supporting rod 30 and its associated movable contact member 13 are restrained.

Other structural features and arrangements and locations of parts may be employed within the spirit and scope of my invention, and I desire that only such limitations shall be imposed as are indicated in the appended claims.

I claim as my invention:

30. 1. A centrifugal device comprising a rotatable member, a weighted arm pivotally connected thereto, a second arm pivotally connected to said rotatable member in substantially parallel relation to said weighted 35 arm, a link connecting the free ends of said arms and a resilient means interposed between said link and a point on said rotatable member between the pivotal points of said arms to normally restrain the parts in their 40 initial positions.
2. A centrifugal device comprising a rotatable member, a weighted arm pivotally mounted thereon, a second arm pivotally connected to said rotatable member, a link, 45 connecting said arms, and a resilient means interposed between said link and a point on said rotatable member between the pivotal points of said arms for restraining said arms and link in their initial positions.
50. 3. A centrifugal device comprising a rotatable member, a weighted arm pivotally mounted thereon, a toggle connecting said arm to said member, and a spring interposed between a point on that member of 55 said toggle which is connected to said weighted arm and an approximately opposite point on said rotatable member to pre-

vent an outward movement of said weighted arm under predetermined speed conditions.

4. A centrifugal device comprising a rotatable member, a pivotally mounted weighted arm associated therewith, a toggle connecting said arm to said member, and a spring interposed between said toggle and an approximately opposite point on said rotatable member to normally act in a direction substantially parallel to the toggle member that is directly attached to said rotatable member.

5. A centrifugal device comprising a rotatable member, a weighted arm pivotally mounted thereon, a second arm also pivotally connected to said member, a link interposed between the free ends of said arm, and a spring connected to said rotatable 75 member and to said link and disposed substantially parallel to said second arm for restraining said weighted arm in its initial position.

6. A centrifugal device comprising a rotatable member, a weighted arm pivotally mounted thereon and adapted to be moved outwardly by centrifugal force, a second arm pivotally mounted on said rotatable member, a link connecting the free ends of 85 said arms and a spring interposed between an intermediate point in said link and an approximately opposite point on said rotatable member to restrain the weighted arm in its inner initial position under predetermined speed conditions and to permit it to be thrown outwardly with a quick movement 90 when said conditions are exceeded.

7. A centrifugal device comprising a rotatable member, a pivotally mounted arm 95 associated therewith and adapted to be moved outwardly by centrifugal force, and means comprising a second pivotally mounted arm, a link between said arms and a spring interposed between the link and the 100 rotatable member and disposed substantially parallel to the second arm to maintain the weighted arm in its initial position under normal speed conditions and to cause a quick outward movement thereof under abnormal 105 speed conditions.

In testimony whereof, I have hereunto subscribed my name this 11th day of June 1912.

STANLEY L. ARMSTRONG.
